UNITED STATES PATENT OFFICE.

JAMES SLAYBAUGH, OF PHILADELPHIA, PENNSYLVANIA.

STAMP-AFFIXER AND ENVELOP-SEALER.

No. 867,216.

Specification of Letters Patent.

Patented Sept. 24, 1907.

Application filed October 16, 1906. Serial No. 339,182.

To all whom it may concern:

Be it known that I, JAMES SLAYBAUGH, a citizen of the United States, residing in Philadelphia, in the county of Philadelphia and State of Pennsylvania, have invented a new and useful Improvement in a Stamp-Affixer and Envelop-Sealer, of which the following is a specification.

This invention relates to devices for the preparation of ordinary, commercial, gummed envelopes, and their inclosures, preparatory to mailing, and has for its objects:—First, the provision of a device to effectually moisten the extended flap of an envelop, fold it over on the body thereof and exert sufficient pressure to cause the adhesive material with which it is provided to unite the folded flap to the body. Second, the provision of a device to contain a supply of postage stamps, automatically separate, convey and affix them to the envelop in proper position thereon. Third, to provide a device readily operated by inexperienced persons, without difficulty, and which will not soil the envelop or person, and fourth, to provide a device of the kind, of neat and attractive appearance, particularly adapted for office uses. These objects are attained by the novel arrangement and combination of parts hereinafter fully described and shown in the accompanying drawings, forming part of this specification, and in which:

Figure 1 is a side view of the entire apparatus. Fig. 2, is a front view of the same. Fig. 3, is a transverse sectional view taken on a line indicated by *a—a* of Fig. 1. Fig. 4, is a side elevation of the stamp carrier supporting device, looking from the interior and drawn to an enlarged scale. Fig. 5, is a plan view of the complete apparatus. Fig. 6, is a transverse sectional view taken on a line represented by *b—b* of Fig. 5. Fig. 7, is a detail of the stamp cylinder revolving means, drawn to an enlarged scale. Fig. 8, is a transverse sectional view taken on a line represented by *c—c* of Fig. 5. Fig. 9, is a horizontal sectional view taken through the casing and stamp cylinder. Fig. 10, is a front view of the complete apparatus. Fig. 11, is a detail of the stamp affixer. Fig. 12, is a detail of the stamp separating device. Fig. 13, is a detail of the spring used in connection with the separating device.

Similar characters refer to similar parts throughout the several views.

The apparatus is adapted to be supported on any convenient surface, as a shelf, desk or table, by means of the standards 1, and 1', which extending upward from the ends 2, and 2', of the semi cylindrical stamp casing 3; at the front end of the machine is the table 4, having at its ends the bearings 5, and 5'; extending downward below the shelf is the fluid reservoir 6, which contains the moistening roller 7, the intermediary roller 8, and the pressure roller 9, which is so arranged as to have its lower edge normally co-incident with the surface of the shelf or table 4.

One end of the roller 9, extends through the bearings 5, and has upon it a pinion 10, acting as an intermediate between the driving gear 11, and the driven gear 12. On the outer surface of the gear 11, is a suitable knob (or crank) 13, adapted to be grasped by the hand to rotate the same, while on the face of the gear 12, is a disk 14, having a cam projection 15, the use of which will be hereafter described.

Within the casing 3, is a decagonal or ten sided roller 16, which is of such length as to accommodate an ordinary full sheet of one hundred stamps. These stamps are placed in position on the roller 16, originally, by operating the knob 17, which extends through the bearings 2', while the front end of the roller 16, revolves in bearings formed in the standard extension 2.

In order that the stamps may be drawn in and around the roller and be retained in their proper position there are provided a series of teeth 18, attached to the plate 18', and arranged, longitudinally, on each of the faces of the roller 16, and so distanced apart as to accommodate the width of a stamp; the said projecting teeth 18, pass in corresponding depressed surfaces in the interior of the casing 3, and between the teeth 40, of the comb-like springs 41, which serves to hold the 80 stamps closely against the roller 16. The teeth 18, also act as a knife in partially separating the strips or rows from the sheet at each partial revolution of the roller 16, the spring teeth 41, pressing the sheet of stamps against the teeth, causing them to shear and entirely separate the rows of stamps as they are rolled on the flat surfaces of the roller 16; each separated row is revolved and carried in turn to the top or upper side of the roller and there held in close relation with it by means of the stamp carriage 19, which, normally, rests on the surface of the stamps. Motion is transmitted to the carrier 19, through the stud 19', connecting rod 20, attached to the stud 21, set in the outer surface of the disk 14, which is secured to the face of the gear 12, and is revolved by the knob 13, through the pinion 10, said motion being sufficient to bring forward the separated row of stamps the proper distance, at each movement, by frictional contact of the exposed stamp surface with the lower side of the carrier 19.

The stamp carrier is sustained in position by the side projection 22, and 22', at its forward end, and 23, and 23', near its rear end, which ride normally on the guideways 24, and 24', 25, and 25', respectively on their forward or advance movement toward the rolls.

When the carrier 19, has reached the limit of its forward action, it is raised, automatically, by means of the springs 26, and 26', at its forward end, and 27, and 27', at its rear end; the same being so placed in relation to the projections 22, and 22', 23, and 23', as to exert their pressure upward at this moment, while on the reverse action of the carrier 19, the projections

ride freely on the guides 24, and 24', 25, and 25', until they have reached the limit of their rearward action, at which time they drop, by gravity, below the extending portion of the guides and are held loosely against the under side thereof by the action of the said springs, yet in contact with the row of stamps; thus each of the projections 22, and 22', 23, and 23', are caused to describe orbits about the inwardly extended portions of the guides, engaging, during their forward motion, with whatever stamps may be disposed upon the surface of the roller 16.

The carrier 19, is maintained in relative position by the caps 28, and 28', at the front end, and 29, and 29' at the rear end.

5 As the stamps are brought forward and reach the limit of their travel, the weighted knife 30, passing over the serrated edge 31, cuts them from the strip and continuing downward presses them upon the previously moistened surface of the envelop in proper 0 position.

The downward action of the knife is accomplished by gravity only, it is raised by means of the plate 32, through the action of the cam 15, and held, when so raised, by the detent 33, until such time as the detent 5 is moved from under it by the forward motion of the envelop striking its lower end. The said detent 33, is supported by the pivot 33^a, set in the standard 33^b, secured to the end of the standard frame 2.

The knife 30, and its parts are held in relative position by means of the lever 34, pivotally attached upon the casing 3, near its rear end, so that the knife in its downward pathway describes a large radius, amounting, in practice, to a vertical motion. The roller 16, is further caused to revolve at such times as the stamps 5 in any one row shall have been exhausted by means of the ratchet 35, said ratchet containing nine teeth formed in the usual manner and one of extra depth, the ratchet being free to rotate on the shaft 42; immediately adjacent to the ratchet 35, is another ratchet 0 35^a, having ten teeth and centered upon a square portion of the shaft 42. Both of these ratchets are adapted to be actuated by the pawl 36^a, kept in contact with the teeth thereof by means of the spring 36^b, both spring and pawl being attached to the lever 36, which 5 is connected by the lever 37, to the plate 32, as is common in automatic devices of this character, such as counting registers and numbering machines—so that if the sheet contains, as is usual, ten rows of ten stamps each, it will bring the next consecutive row into position for operation when the preceding row has been exhausted.

Provision for maintaining the roller 16, in position, is provided for, at the rear end, by the disk 43, centered on the square portion of the shaft 42^a, which 55 further extends through to its bearings in the rear casing 2', and has attached to it the knob 17; the disk 43 is provided with ten depressions, adapted to receive the roller 44, nominally pressed therein by means of the spring container 45, attached to the outer shell 30 or casing 3.

In operation, the fluid reservoir, being filled with a suitable liquid, as water, in which the roller 7, revolves; a certain amount of moisture is taken and transferred therefrom to the intermediate roller 8, 65 which is adapted to moisten the extended flap of the

envelop as it passes over it; previous to passing over the roller the intermediate roller has transferred in turn to the upper roller a certain amount of moisture, to be taken on the face of the envelop preparatory to receiving the stamp; as the envelop is advanced 70 the flap contacts with the roller 39, held in position by the spring plate 38, attached to the underside of that part of the table which projects rearwardly from the roller, causing the flap to enter the groove or slot-way 4^a immediately adjacent to the roller and formed 75 in the rear portion of the envelop table, while the front part of the envelop, being relatively stiffer or less yielding, projects over the rear table surface until it contacts with the detent 33, at which time the flap has been withdrawn from the slot and properly positioned against the envelop; on the reverse movement of the knob 13, the flap is brought in close contact with the lower side of the envelop, passing between the rollers 8 and 9, being effectually sealed thereby, as well as having the stamp pressed to the face of the 80 envelop; thus when the envelop has been inserted, the knob 13, operated, it is advanced, moistened, folded and caused to receive the stamp, while the reverse action presses the moistened flap and stamp securely to the envelop. I may make these rollers of 85 such material, diameter and length as may seem appropriate for the purpose, and the moistening roller may be made partially of non-absorbent material and the remainder may be made of such material as may be readily saturated by the moisture conveyed to it. 90

I do not claim broadly the use of such rollers or of fluids conveying mediums, neither do I claim the means used in conveying revolution to the stamp containing device, but

What I do claim and desire to secure by Letters 100 Patent is:

1. The combination with a suitable framework and means combined therewith for manipulating envelops, of a decagonal roller adapted to hold a sheet of postage stamps, and having a series of teeth at each angle thereof, means 105 for separating rows of stamps from the sheet, means for conveying such separated row into position for affixing on an envelop and means for separating individual stamps from the row and affixing said stamps to the envelop.

2. In a stamp affixing machine, a revoluble stamp holding cylinder, having a plurality of flat facets and provided at the angles thereof with a series of laterally disposed teeth, means for manually operating said cylinder, and means for automatically operating said cylinder, a reciprocating stamp carrier arranged laterally of the said cylinder, means for oscillating the said carrier so that the same shall exert a downward pressure during its forward movement and be released therefrom during its rearward movement and means for separating and affixing the stamps, substantially as specified. 110

3. In an apparatus for folding, moistening and sealing gummed envelopes and affixing stamps thereto, the combination with a level table, having central longitudinal opening, a fluid reservoir below said opening, fluid, conveying rollers below the level of said table, a pressure roller above said opening and means for manually operating the same, of a spring controlled, depression roller, partially over the table and partially over the opening therein, arranged rearwardly of the moistening roller and adjacent to the edge of the table, means to bring a stamp into registration with the corner of an envelop, means for depositing it in proper location and means for pressing the flap and stamp to the body of the envelop, co-incident to its withdrawal. 125

4. In a stamp affixer, a frame, a roller journaled therein, 130 having a plurality of flat facets, each combined with edged

serrations and adapted to contain a row of stamps, a spring member co-acting with said serrations to separate an entering sheet of stamps into rows, a carrier disposed on the frame in such manner as to exert frictional contact 5 with the top row of stamps in one direction only, means for imparting reciprocating motion to the said carrier, a gravity operated cutter for separating the rows into individual stamps, means for elevating said cutter, means for holding the cutter when so raised and means for releasing 10 the said cutter co-incident with and upon the proper

positioning of a receiving envelop, all substantially as shown and described.

In testimony whereof, I have hereunto signed my name to this specification, in the presence of two subscribing witnesses.

JAMES SLAYBAUGH.
